Primary Examiner — Elizabeth A. Albert(74) *Attorney, Agent, or Firm* — Craft Chu PLLC;
Andrew W. Chu(57) **CLAIM**

The ornamental design for a corkscrew, as shown and described.

DESCRIPTION

FIG. 1 is an upper perspective view of the corkscrew showing my design;

FIG. 2 is a side elevation view thereof, an opposite side elevation view being a mirror image thereof;

FIG. 3 is a front elevation view thereof, a back elevation view being a mirror image thereof;

FIG. 4 is a bottom plan view thereof; and,

FIG. 5 is a top plan view thereof.

The broken lines in FIG. 4 represent portions of the corkscrew that form no part of the claimed design.

1 Claim, 2 Drawing Sheets(56)
